ELECTRIC HEATER

James J. Geugh, Chicago, Ill., assignor to Chicago Electric Manufacturing Company, Chicago, Ill., a corporation of Illinois

Application July 22, 1939, Serial No. 286,004

5 Claims. (Cl. 312—34)

This invention relates to electric heaters and particularly to heaters of the portable room-heating type.

It is an object of the invention to provide a portable electric heater of improved and simplified construction in which the various structural parts can be readily and economically fabricated and assembled, while producing a wholly satisfactory and durable heater structure.

10 It is a further object of the invention to provide a portable electric heater of improved safety and, more particularly, to provide a heater structure which will not set fire or constitute a fire hazard with respect to adjacent objects, no matter in what position the heater is placed or even in the event that the heater structure is inadvertently upset or otherwise displaced from its normal upright position.

15 A still further object of the invention is to provide a portable electric heater construction having a handle structure which may be moved to a retracted position to facilitate shipment or the like, but which can also be readily moved to and releasably retained in an extended or operative position, in which position it may be grasped by the user to facilitate movement of the heater from place to place as may be desired.

20 Various other objects, advantages, and features of the invention will appear from the following specification when taken in connection with the accompanying drawings, wherein a preferred embodiment of the invention is illustrated.

25 In the drawings, wherein like reference numerals refer to like parts throughout:

30 Figure 1 is a general assembly view in front perspective illustrating a portable electric heater constructed in accordance with the principles of the invention;

35 Fig. 2 is a detailed view of the handle structure showing the handle in extended or operative position;

40 Fig. 3 is a view illustrating the handle in retracted position, as for shipment;

45 Fig. 4 is a detailed view showing the wire guard member which forms a part of the construction;

50 Fig. 5 is a partial sectional view of the structure shown in Figure 1 on the line 5—5 thereof;

55 Fig. 6 is a side view of the heater illustrating the position which will automatically be assumed by the structure in the event that it is knocked or displaced from normal upright position;

Fig. 7 is a sectional view of the structure shown in Figure 1 on the line 7—7 thereof; and

Fig. 8 is a sectional view on the line 8—8 of Figure 7, the central portions of the heater including the handle structure having been broken away.

Referring more particularly to the drawings, it will be seen that the heater structure illustrated comprises in general a main frame 10, a wire guard 11, and a reflector structure 12 carrying the heating elements 13 at the lower end thereof in a manner to be later more specifically described.

The main frame comprises a sheet metal piece 14 bent into general U shape, whereby to form the front and back walls and the top portions of the heater, and a pair of side sheet metal pieces 15 and 16 (Fig. 8) which form the side walls for the structure. The side walls are provided with inwardly directed flanges 17 and 18 as best seen in Figs. 1 and 8, these flanges being adapted to be spot-welded or otherwise suitably secured to the sheet metal piece 14, whereby to provide an economically fabricated, rigid, unitary frame structure.

The side walls are provided with extensions 19 at the lower ends thereof, the extensions being turned inwardly, as best shown in Fig. 8, whereby to provide a series of feet upon which the heater may rest in spaced relation to the floor or other supporting surface. The feet members, which thus constitute merely integral stamped and bent extensions at the lower ends of the side walls, constitute an effective means for supporting the heater in slightly spaced relation to the supporting surface, whereby to facilitate circulation of air underneath the construction and to maintain the main body of the frame parts out of contact with the supporting surface to minimize the transmission of heat thereto. In the embodiment illustrated, four such feet are provided, two extensions 19 being provided at the lower end of the side walls 15 and 16.

The front wall of the sheet metal main frame piece 14 is provided with louvers or the like, as indicated at 20, and the side walls may be provided with ribbing, such as indicated at 21 (Fig. 1) conforming to the contour or outer shape of the side walls. The louvers not only enhance the appearance of the construction but also serve as means for facilitating the circulation of air through the front wall of the heater. The louvers and the ribbing 21 may be readily stamped or pressed during the formation of the sheet metal pieces with which they are associated. The upper rear wall of the sheet metal piece 14 is also

provided with a series of stamped openings 22 (Figs. 7 and 8) to facilitate the circulation of air through the upper rear heater wall. The openings 22 thus constitute means for permitting an 5 upward draft of air through the heater along the rear side of the reflector structure.

For purposes of ornamentation, the front wall of the heater is provided with an ornamental strip 23 arranged between the louvers 20, and the side 10 walls 15 and 16 are provided with strips 24 and 25, respectively (Fig. 8). The strip 23 may be secured in position by the simple expedient of clinching its lower and upper ends 26 and 27 (Figs. 1 and 7) around the associated sections of 15 the front heater wall. Similarly, the side strips 24 and 25 are retained in position by clinching their lower ends 28 and 29 and their upper ends 30 and 31 into engagement with the respective side walls, the side walls to this end being provided 20 with stamped slits into which the strip ends 30 and 31 may be inserted. The foregoing constitutes a simplified means for securing the strips in position and yet effectively holds them in place. The louvers 20 prevent lateral displacement of 25 the strip 23. The side strips 24 and 25 are prevented from lateral displacement at their upper ends by the slits into which their upper ends are inserted and at their lower ends by slightly indented sections 32 (Fig. 7) formed in the lower 30 edge of the side walls.

As best shown in Figs. 1, 2, and 3, the handle 33 is adapted to occupy an extended or operative position as shown in Fig. 2 or a retracted inoperative position as shown in Fig. 3. The handle 35 may be retracted as in Fig. 3 during shipment, thus facilitating the insertion or arrangement of the heater within a shipping container. When set up for use, the handle may be pulled to the extended position shown in Fig. 2, in which position it may be readily grasped by the user rendering the heater readily portable from place to place. In accordance with the invention, the handle is adapted to be releasably held in extended position and, to this end, is provided with 40 a U-shaped bracket part 34 adapted to project through openings 35 in the sheet metal piece 14 and is also provided with struck-out projections 36. When the handle is pulled to the operative position shown in Figure 2, it will be releasably 45 held in such position by reason of the engagement of the projections 36 against the top of the sheet metal piece 14, the projections being slightly larger than the openings 35. However, the handle may be moved to retracted position 50 if a definite downward force is applied thereto. When the handle is extended, as shown in Figure 2, it is maintained in spaced relation from the main body of the heater frame, thus imparting maximum cooling thereto.

60 The guard structure 11 is best shown in Figure 4. As illustrated, it comprises a fabricated wire structure 11 consisting of a frame piece 37 and horizontal and vertical wires 38 and 39 welded or otherwise secured together to form a comparatively rigid guard structure. The vertical wires are provided at their upper and lower ends with extensions 40 and 41, respectively, by which the guard may be readily and removably attached to the opening in the sheet metal frame piece 14 65 with which it is associated. While the guard structure is comparatively rigid, it is sufficiently resilient to permit the wire ends 40 and 41 to be sprung under the bead of the frame opening, the resiliency of the guard serving to hold it in proper 70 position after assembly. The horizontal wires 38

are also provided with extensions 42 and 43 which project into the frame opening and serve to center the guard with respect thereto when in assembled position.

The particular shaping of the guard in combination with the center of gravity of the heater structure constitutes an important feature of the invention. As best shown in Fig. 6, in the event the heater structure is upset or otherwise displaced from its upright position in such a manner 10 as to fall forwardly, the structure will automatically assume the position shown in which the heat, directed outwardly through the frame opening by means of the reflector 12 and its associated heating elements, will be prevented from 15 directly impinging the supporting surface diagrammatically illustrated in Figure 6 by the reference numeral 44. In other words, the heat rays are caused to be directed angularly away from the supporting surface so that, even though 20 the heater should remain in upset position indefinitely, the supporting surface will not catch fire.

It is further to be noted that, due to the convex shaping of the vertical wires 38 from a position of maximum displacement from the heater body at their lower ends to a point of minimum displacement at their upper ends, the heater will automatically roll to the position shown in Fig. 6, even though it should initially fall forward 25 into a substantially horizontal position or into position wherein the upper end of the heater was lower than the lower end thereof. The center of gravity of the structure is at a position substantially as indicated at 45, so that if the heater 30 were to fall or be knocked forward to a greater degree than the position shown in Fig. 6, it would automatically rock back to the position shown in Fig. 6, wherein the heat rays, projected outwardly through the frame opening, would be 40 deflected from the supporting surface, as previously described.

When in normal upright position, the lower end of the guard projects sufficiently forward from the front wall of the heater, whereby to 45 preclude the heater being placed in too close proximity to a vertical wall or surface. The guard 11, due to its shape, thus protects against fire hazard when the heater is in normal upright position or in the event it should fall forwardly, 50 the arrangement being such that in any forward fall the construction will automatically assume the safety position illustrated in Fig. 6.

The reflector structure is best shown in Figs. 5, 7, and 8 and comprises, in addition to the 55 main U-shaped reflector piece 12, a pair of side plates 46 and 47 (Fig. 8) flanged as indicated at 48 and 49 and suitably secured to the piece 12 as by spot welding 50. The reflector structure may be mounted upon the main frame by suitable means, such, for example, as the three screws 51, 52, and 53.

The reflector piece 12 is provided at its lower forward portion with a series of openings 54 which, in cooperation with the main frame 65 louvers 20, facilitate an upward draft of air through the heater along the front of the reflector and outwardly through the wire guard and associated frame opening. The inner surface 55 of the reflector piece 12 may be plated 70 or polished in any suitable manner and corrugated, if desired, to diffuse the heat rays. The reflector piece 12 also carries a series of refractory supports 56 and 57 which form the supporting means for the heating element 13 75

which, in the particular embodiment shown, constitutes a coiled resistance wire. The wire in turn holds the supports 56 and 57 in position, the supports otherwise being freely removable 5 through the reflector wall 12. The enlarged bases of the supports prevent the inward movement thereof, while permitting the free withdrawal of the supports when the supports are dissociated from the wire 13. Wires 58 connect 10 the heating element or wire 13 to terminals carried by and insulated from a bracket 59 which terminals in turn are connected to the electrical supply leads 60. The bracket mounting the terminals 59 is supported by means of screws 61 on a base plate 62, the forward end of the base plate being in turn secured to the reflector piece 12 by means of screws 63. The base plate is also provided with a projection 64 forming a support means for the reflector 12. The rear flange 65 15 of the base plate rests upon an in-turned flange 66 formed at the lower rear edge of the main frame piece 14.

It is obvious that various changes may be made in the specific embodiment of the invention set forth for purposes of illustration without departing from the spirit thereof. Accordingly, the invention is not to be limited to the precise embodiment shown and described, but only as indicated in the following claims.

30 The invention is hereby claimed as follows:

1. An electric heater of the type adapted to be removably rested upon a supporting surface, said heater comprising a casing having a generally rectangular front and rear wall and a substantially rectangular opening disposed in the front wall of the casing having a lower margin disposed below the median point of said front wall, a heating element within the casing and disposed to direct radiated heat outwardly through 35 said opening, and a guard grill across the opening, said grill having a lower planar portion projecting generally horizontally outwardly at a sharp angle adjacent the lower margin of said opening to a substantial distance in front of the front wall, said grill having a portion extending in a curved plane upwardly and rearwardly from the outer extremity of said outwardly projecting lower portion to the upper margin of said opening and being outwardly convexly curved 40 throughout the upwardly extending portion, said heater being constructed and arranged with its center of gravity below said lower margin of the opening and operative to exert a force causing said heater to roll to a position with the lower portion of the guard grill contacting the supporting surface if the heater becomes tipped over.
2. An electric heater of the type adapted to be removably rested upon a supporting surface, said heater comprising a casing having a generally rectangular front and rear wall and a substantially rectangular opening disposed in the front wall of the casing having a lower margin disposed below the median point of said front wall, a heating element within the casing and disposed for directing radiated heat outwardly 45 through said opening, and a guard grill across the opening, said grill having a lower planar portion projecting outwardly generally horizontally at a sharp angle adjacent the lower margin of said opening to a substantial distance in front of the front wall, said grill having a portion extending in a curved plane upwardly and rearwardly from the outer extremity of said outwardly projecting portion to the upper margin of said opening and being outwardly convexly curved 50 throughout the upwardly extending portion, said heater being constructed and arranged with its center of gravity below said lower margin of the opening and operative to exert a force causing said heater to roll to a position with the lower portion of its front wall contacting the supporting surface when the said heater is arranged with said convex portion upon a supporting surface, the lower margin of the opening being substantially spaced from the lower extremity of said front wall but substantially below the median horizontal plane of the heater.
3. An electric heater of the type adapted to be removably rested upon a supporting surface, said heater comprising a casing having upstanding front, rear and side walls and a substantially rectangular opening disposed in the front wall 55 of the casing and having a lower horizontal margin and opposed vertical margins, a heating element within the casing and disposed for directing radiated heat outwardly through said opening, and a guard grill across the opening, said grill having a lower planar portion projecting in a direction substantially normal to the front wall from said lower margin to a point substantially outwardly of said front wall, said grill having a convex portion extending in a curved plane upwardly and rearwardly from the outer extremity of said outwardly projecting portion to the upper margin of said opening, said heater being constructed and arranged with its center of gravity below said lower margin of the opening and operative to exert a force causing said heater to roll to a position with the lower portion of its front wall contacting the supporting surface when the said heater is arranged with said convex portion upon a supporting surface, the lower margin of the opening being substantially spaced from the lower extremity of said front wall but substantially below the median horizontal plane of the heater.
4. An electric heater of the type adapted to be removably rested upon a supporting surface, said heater comprising a casing having upstanding front, rear and side walls and a substantially rectangular opening disposed in the front wall 60 of the casing and having a lower horizontal margin and opposed vertical margins, a heating element within the casing and disposed for directing radiated heat outwardly through said opening, and a guard grill across the opening, said grill having a lower planar portion projecting in a direction substantially normal to the front wall from said lower margin to a point substantially outwardly of said front wall, said grill having a convex portion extending in a curved plane upwardly and rearwardly from the outer extremity of said outwardly projecting portion to the upper margin of said opening, said heater being constructed and arranged with its center of gravity below said lower margin of the opening and operative to exert a force causing said heater to roll to a position with the lower portion of its front wall contacting the supporting surface when the said heater is arranged with said convex portion upon a supporting surface, the lower margin of the opening being substantially spaced from the lower extremity of said front wall but substantially below the median horizontal plane of the heater.
5. An electric heater of the type adapted to be removably rested upon a supporting surface, said heater comprising a casing having upstanding front, rear and side walls and a substantially rectangular opening disposed in the front wall 65 of the casing and having a lower horizontal margin and opposed vertical margins, a heating element within the casing and disposed for directing radiated heat outwardly through said opening, and a guard grill across the opening, said grill having a lower planar portion projecting in a direction substantially normal to the front wall from said lower margin to a point substantially outwardly of said front wall, said grill having a convex portion extending in a curved plane upwardly and rearwardly from the outer extremity of said outwardly projecting portion to the upper margin of said opening, said heater being constructed and arranged with its center of gravity below said lower margin of the opening and operative to exert a force causing said heater to roll to a position with the lower portion of its front wall contacting the supporting surface when the said heater is arranged with said convex portion upon a supporting surface, the lower margin of the opening being substantially spaced from the lower extremity of said front wall but substantially below the median horizontal plane of the heater.

of the casing and having a lower margin disposed below the median point of the wall, a heating element within the casing and disposed for directing radiated heat outwardly through said opening, and a guard grill across the opening, said grill having a lower planar portion projecting in a direction substantially normal to the front wall from said lower margin to a point substantially outwardly of said front wall, said 10 grill having a second portion extending in a curved plane upwardly and rearwardly from the outer extremity of said outwardly projecting

portion to the upper margin of said opening and being outwardly convexly curved, said heater being constructed and arranged with its center of gravity below said lower margin of the opening and operative to exert a force causing said heater to roll to a position with the lower portion of its front wall contacting the supporting surface when the said heater is arranged with said convex portion upon a supporting surface, the lower margin of the opening being substantially 10 centrally disposed in said front wall.

JAMES J. GOUGH.
